UNITED STATES PATENT OFFICE.

FRANK HOLTON, OF ELKHORN, WISCONSIN.

TUNING SLIDE FOR MUSICAL INSTRUMENTS.

Application filed May 5, 1924. Serial No. 710,972.

This invention relates to wind instruments in which the tone is controlled by the length of an air column and has for its object the provision of means for quickly adjusting the 5 column length to properly tune the instrument.

The invention is shown as applied to a 10 trombone, but it will be readily apparent that it may be applied to various instruments 15 having pipes or tubes for controlling the length of a vibrating air column.

The invention is exemplified in the combination and arrangement of parts as shown in the accompanying drawing and described 15 in the following specification, and it is more particularly pointed out in the appended claims.

In the drawing—

Fig. 1 is an elevation of a trombone having one embodiment of the present invention 20 applied thereto; and

Fig. 2 is a fragmentary elevation of the tuning slide shown on a larger scale than that of Fig. 1.

25 In the drawing, the numeral 10 designates the bell of a trombone having a slide 11 movable in and out on the tubes 13 and 14 in the usual manner. The slide 11 is a hollow tube bent back upon itself, the back- 30 wardly extending ends being slidable on tubes 13 and 14 which project forwardly from the tube 12 and the portion 15, respectively, the portion 15 having a mouthpiece 16 thereon.

35 The rearwardly extending projecting ends of the slide 11 are provided with tuning sleeves 17 and 18 which are mounted to slide on the ends of the tubes 11 so as to change the effective length of the slide. The sleeve 40 17 has a toothed rack 19 secured thereto arranged to be engaged by the nose 20 of a detent arm 21. The arm 21 is pivoted at 22 to a cross-bar 23 which connects the ends of the slide 11. A finger piece 24 extends 45 downwardly from the arm 21 and is provided with a spring 25 which resiliently holds the nose 20 in engagement with the rack teeth 19. A skeleton frame 26 encloses the arm 21 and provides a slide 27 for guiding the arm 21 in its movement along the rack 19.

When it is desired to change the pitch of the instrument it is only necessary for the operator to press the finger piece 24 and 50 move the slide 11 in the sleeves 17 and 18. This increases and decreases the effective

length of the slide 11 so that the correct tone will be secured at the proper position of the slide on the tubes 13 and 14. It is frequently desirable to correct the tuning of the 60 trombone without loss of time incident to operation of screws and nuts for changing the relative position of parts and the present invention provides means by which the tuning is accomplished substantially instantaneously. 65 If, for instance, the instrument is cold when the musician begins to play and becomes warm during the performance the parts will expand and the tone will consequently be changed. This may be corrected instantly 70 by merely pressing the finger piece 24 and moving the parts 17 and 18 relative to the slide 11. The correction may be made without interrupting the performance. A stop 28 is provided at the end of the rack 19 to 75 prevent the tuning slide from being entirely withdrawn from the trombone slide 11. It will be apparent that the holding member 20 with its rack and associated parts can be duplicated on the other arm of the slide if 80 found desirable. In this case the finger pieces 24 will overlap so that both catches may be released by pressing a single finger piece.

I claim:

1. A wind musical instrument having a sliding tone passage, a sliding extension for said passage, and means for changing the adjustment of said extension while playing said instrument.

2. A wind musical instrument having a sliding tone passage, a sliding extension for said passage, and means for changing the adjustment of said extension when engaging the tone passage to slide the same.

3. A wind musical instrument having a sliding tone passage, a sliding extension for said passage, and means for sliding the tone passage and simultaneously changing the adjustment of said extension.

4. A wind musical instrument having a sliding tone passage, a sliding extension for said passage, and means for sliding the tone passage and simultaneously changing the adjustment of said extension comprising a 105 cross-bar between two parallel lengths of said extension for the tone passage, a detent mounted on said cross-bar, and a plurality of spaced stops on the tone passage for engaging said detent.

5. A wind musical instrument having a sliding tone passage, a sliding extension for

said passage, and means for sliding the tone passage and simultaneously changing the adjustment of said extension comprising a cross-bar between two parallel lengths 5 of said extension for the tone passage, a detent on said cross-bar, a plurality of spaced stops on the tone passage arranged to be engaged by said detent, and a finger-piece for moving said detent out of engagement 10 with said stops to release said extension for sliding movement, said finger-piece being positioned whereby the same may be actuated by the player while his hand is in a position to slide the tone passage when playing the instrument.

6. A wind musical instrument having a sliding tone passage, a sliding extension for said passage, and means for sliding the tone

passage and simultaneously changing the adjustment of said extension comprising a rack secured to said tone passage, a bell crank lever pivoted to the extension for said tone passage, said bell crank lever having a nose-piece for engaging said rack, a spring for holding said nose-piece in contact with said rack, and a limit stop for engaging said nose-piece to prevent separation of the extension from the tone passage, said bell crank lever being positioned whereby the same may be actuated by the player while his hand is in a position to slide the tone passage while playing the instrument.

In testimony whereof I have signed my name to this specification on this 2d day of May, A. D. 1924.

FRANK HOLTON.
